[57] **ABSTRACT**

A glove box includes a housing having an opening formed therein. A bag is disposed on the housing covering the opening. The bag is single-layered and formed of a weldable thermoplastic polyurethane with physically reversibly cross-linked fusible molecules.

GLOVE BOX FROM POLYURETHANE

CROSS-REFERENCE TO RELATED APPLICATION

This application is a continuation-in-part of application Ser. No. 758,352, filed Sep. 9, 1991, which was a File Wrapper continuing application of application Ser. No. 222,269, filed Jul. 21, 1988 both now abandoned.

BACKGROUND OF THE INVENTION

1. Field of the Invention

The invention relates to a glove box, having a housing opening at which a bag, in particular a gas-tight glove, a gas-tight outward transfer bag or a gas-tight connection bag for connection to a container, is disposed.

2. Description of the Related Art

A glove box of this type is known from German Published, Non-Prosecuted Application DE-OS 32 01 976. The gas-tight bag in that known glove box is a glove having a matrix that has a surface coating of halogen-free elastomer and/or polyolefin on the active inner surface of the glove. The polyolefin may be polyethylene, while a surface coating of chlorosulfonated polyethylene may be disposed on the matrix on the inactive outer surface of the glove.

If work is done with radioactive emitters in the prior art glove box, in particular alpha emitters such as plutonium, then the surface coating of halogen-free elastomer and/or polyolefin on the active inner surface of the glove prevents halogens, in particular chlorine, from being liberated by the radioactive radiation on the active inner surface of the glove and from reaching the glove box and thus the radioactive emitter.

Keeping the radioactive emitter free of halogen contamination avoids corrosion of metal enclosures into which the radioactive emitter is introduced, which is caused by halogens emitted by the radioactive emitter. This is particularly important where the radioactive emitter is in the form of pellets of plutonium or mixed plutonium oxide, which are used as nuclear fuel in existing cladding tubes, for example those made of a zirconium alloy, in fuel rods of a nuclear reactor fuel assembly. During use in a nuclear reactor, greater corrosion damage must be expected in these cladding tubes, if the nuclear fuel emits halogens.

Although glove boxes having single-layer gas-tight bags disposed at housing openings are already known,

From U.S. Pat. No. 4,141,609 to Eisert there is known a glove box with a glove, the arm of which is formed of a sprayed polyurethane elastomer. Such sprayable polyurethane elastomers belongs to the group of casting elastomers and it has chemically cross-linked, i.e. irreversibly cross-linked, molecules. The material is neither thermoplastic nor can it be melted down, i.e. it cannot be welded.

It is accordingly an object of the invention to provide 10 a glove box, which overcomes the hereinafore-mentioned disadvantages of the heretofore-known devices of this general type and which refines the prior art glove box by providing a gas-tight bag of single-layer material.

15 SUMMARY OF THE INVENTION

With the foregoing and other objects in view there is provided, in accordance with the invention, a glove box, comprising a housing having an opening formed 20 therein, and a bag disposed on the housing covering the opening, the bag being formed of single-layered, weldable thermoplastic polyurethane with physically reversibly cross-linked fusible molecules. The bag may be a gas-tight glove, a gas-tight outward transfer bag, or a 25 gas-tight connection bag for connection to a container.

The thermoplastic polyurethane used for the bag of the glove box is a thermoplastic polyurethane elastomer. It does not contain any halogen and consequently cannot contaminate radioactive emitters processed in 30 the glove box with halogen. In the case of an outward transfer bag that must later be combusted in the course of waste disposal, corrosion of the combustion furnace is also avoided, because of the absence of halogen. Furthermore, the bag of the thermoplastic polyurethane 35 elastomer is distinguished by great elasticity and high resiliency, so that a very tight fit on a connector stub located at the housing opening of the glove box can be attained with the bag. The bag of the thermoplastic polyurethane elastomer also has great resistance to tearing, great elongation when tearing, and great puncture 40 resistance, so that it can only be damaged with difficulty, if at all, by mechanical implements, such as pointed objects. Finally, the bag of the thermoplastic polyurethane elastomer can be readily welded with 45 highfrequency welding apparatus, it is resistant to abrasion, it is s ideable and it does not stick.

In accordance with an added feature of the invention, the thermoplastic polyurethane has the following basic structure:

where x and y are integers.

In accordance with a concomitant feature of the invention, the thermoplastic polyurethane has the following basic structure:

these known gas-tight bags are formed of polyvinyl chloride. This means that they emit undesirable chlorine to radioactive emitters in the glove boxes. British Patent No. 2,148,094 also discloses a multi-layer pol-

urethane-rubber glove with a woven reinforcing fabric, which is used for work in the kitchen or in the medical field.

where $n = 1,2,3 \dots$, R^1 is an isocyanate radical, R^2 is a chain extender radical, and R^3 is a radical of diol of molar mass 1000 to 3000, and preferably of 2000.
